DUPLEX WIRE COILING MACHINE

Carl E. Spaulding, Worcester, Mass.

Application April 2, 1942, Serial No. 437,436

6 Claims. (CL. 153—65)

This invention relates to wire coiling machines of the general type in which a wire is caused to bend or coil itself about a fixed arbor or mandrel by its own positive forward movement. In such machines, the wire is fed from a continuous supply, as by driven feed rolls, and is forced against a fixed coiling point or abutment, located adjacent a fixed arbor or mandrel. The wire is diverted by the coiling point in such manner that it automatically coils itself about the arbor. The pitch of the coil or spring is determined by a pitch tool, which is adjustable lengthwise of the arbor to vary the pitch. Such machines are commercially well known and one such machine is shown in the expired patent to Sleeper, No. 1,266,070, issued May 14, 1918.

It is the general object of my present invention to increase the capacity of such coiling machines by making them in duplex form. To the attainment of this general object, I provide improved devices for simultaneously adjusting the two pitch tools used in my improved machine, and also for adjusting each tool independently. I also provide an improved construction for driving the two sets of feed rolls used in my new machine.

My invention further relates to arrangements and combinations of parts which will be herein-after described and more particularly pointed out in the appended claims.

Preferred forms of the invention are shown in the drawings, in which

Fig. 1 is a partial side elevation of my improved duplex wire coiling machine;

Fig. 2 is a partial plan view, looking in the direction of the arrow 2 in Fig. 1;

Fig. 3 is a right-hand end elevation, looking in the direction of the arrow 3 in Figs. 1 and 2;

Fig. 4 is a plan view, looking in the direction of the arrow 4 in Fig. 3;

Fig. 5 is a detail sectional side elevation, taken along the line 5—5 in Fig. 3;

Fig. 6 is a plan view showing two pitch tools and simultaneous adjusting mechanism therefor;

Fig. 7 is a side elevation, looking in the direction of the arrow 7 in Fig. 6;

Fig. 8 is a detail sectional plan view, taken along the line 8—8 in Fig. 7;

Fig. 9 is a perspective view of a pitch tool holder to be described;

Fig. 10 is a plan view similar to Fig. 6 but showing a modified construction; and

Fig. 11 is a side elevation, looking in the direction of the arrow 11 in Fig. 10.

Referring particularly to Figs. 1 and 2, my im-

proved duplex machine comprises a fixed frame 10 in which grooved feed rolls 11 and 12 are rotatably mounted. The lower feed rolls 11 are mounted on a cross shaft 14 (Fig. 3) supported in fixed bearings in the frame 10, and the upper feed rolls 12 are mounted on separate cross shafts 15 rotatable in separate bearing blocks 16 (Figs. 1 and 3) each of which is capable of vertical movement in the frame 10 and each of which is limited by a stop screw 17 which may be adjusted to provide the desired pressure on a given size of wire W to be coiled.

A segmental mandrel or arbor 20 (Figs. 1 and 2) for each pair of feed rolls is mounted in fixed position in the frame 10, and a coiling point or deflecting abutment 21 for each arbor is mounted in a slide 22 which may be adjusted forward or backward by a screw 23 which engages a pivoted adjusting arm 24. By adjusting the coiling points 21 toward or away from the mandrels 20, the diameter of the coil at each side of the machine may be decreased or increased as desired.

A cut-off tool 25 for each wire W is mounted in a swinging holder 26 and may be swung toward its associated mandrel 20 to cut the wire at the end of each coil, when and as desired. For a coil of the opposite hand, the cut-off tool 25 may be mounted in a second and upper swinging holder 26^a.

A pitch tool 30 is mounted closely adjacent each mandrel 20 and also adjacent to each coiling point 21, and each pitch tool determines the pitch of the coil or spring wound on its associated mandrel. By adjusting the pitch tool axially of the mandrel and toward or away from the frame 10, the pitch or spacing of the coils may be decreased or increased as desired.

Grooved guide-plates 32 direct the wires W to the feed rolls 11 and 12, and similar grooved guide-plates 33 are provided to direct the wires W from the feed rolls to the mandrels 20, coiling points 21 and pitch tools 30.

For a more complete description of this general method of coiling wire, reference is made to the prior patent to Sleeper of record. The Sleeper patent, however, discloses a single coiling mechanism only, whereas in my improved machine, as shown herein, all of the wire manipulating devices are duplicated at the opposite sides of the machine and the capacity of the machine is doubled.

It is necessary that both the lower feed rolls 11 and the upper feed rolls 12 be positively rotated at equal surface speeds, and one feature

of my invention relates to the provision of improved mechanism for positively driving the two upper feed rolls 12 and at the same time permitting each feed roll to have a slight independent vertical movement to accommodate different sizes of wire.

My improved driving mechanism is shown in Figs. 2 to 5 and comprises the usual drive shaft 40, gear 41 and pinion 42 usually found in such machines. The pinion 42 is fast on the cross shaft 14 which supports the lower feed rolls 11, and these rolls are thus positively and simultaneously rotated.

A gear 44 is mounted on the shaft 14 and approximately at the center of its length and engages a similar and equal gear 45 having extended hub portions 46 rotatable in spaced side portions of a fixed bearing block 47. The inner ends of each upper feed roll shaft 15 are reduced in diameter, as indicated at 50, so that they pass freely through axial openings 51 in the hubs 46 of the upper driving gear 45 and with substantial clearance.

At their extreme inner ends, the driving shaft portions 50 are connected by universal joints 52 to the driving gear 45, so that the shafts 15 will be positively and simultaneously rotated and will also each be capable of slight angular displacement of its axis with respect to the axis of the gear 45. The driving gears 44 and 45, however, rotate in fixed spaced relation and on fixed parallel axes, so that the best driving conditions are continuously maintained.

It is customary to provide the feed rolls 11 and 12 with a plurality of grooves of different cross-sectional radii, which largely takes care of differences in diameters of wires and without substantially increasing the upward movements of the feed rolls 12 for larger wires.

My improved driving mechanism, as above described, is positive and effective and applies the power to the independently movable upper feed rolls 12 in a very reliable and mechanically satisfactory manner.

It has been previously stated that the pitch of the coils or springs wound on the mandrels 20 may be varied by adjusting the pitch tools 30 outward or inward with respect to the frame 10. In Figs. 6 to 9 I have shown mechanism by which the pitch tools 30 at the two sides of the machine may each be given an independent initial adjustment, and by which both tools may be thereafter simultaneously adjusted when and as desired.

Referring to Figs. 6 to 9, each pitch tool 30 is formed at the end of a rod 60 slidable in a fixed bearing in the frame 10. The inner end of each rod 60 is adjustably secured in a tool holder or block 61 (Fig. 9) which may be slotted as indicated at 62 and provided with upper and lower openings 63 and 64 to receive the rods 60. Each rod 60 is placed in an upper opening 63 or in a lower opening 64, according to the hand of the coil or spring to be wound by said pitch tool, and may be clamped in adjusted axial position in said opening by tightening a clamping screw 65 (Figs. 6 and 7).

Each block 61 is connected by a stud 66 to the lower end of an arm 67 or 67^a, mounted to swing about a fixed pivot stud 68. Each arm 67 or 67^a has a laterally extended slotted arm 69 or 69^a, connected by a clamping screw 70 to an arm 71 or 71^a, which arms are also pivoted on the studs 68 and extend laterally therefrom.

The inner ends of the arms 71 and 71^a are 75

halved together, as indicated in Fig. 6, and the arm 71 has a stud 72 extending through a slot 73 in the arm 71^a and to which stud an operating rod 75 is pivotally connected. The rod 75 is normally pressed upward by a stiff spring 76 and such movement is limited by an adjustable threaded stop collar 77 on the rod 75.

The working positions of the two pitch tools 30 may obviously be simultaneously adjusted by 10 changing the setting of the stop collar 77 on the threaded rod 75, and the position of each pitch tool 30 may be independently adjusted, either by 15 sliding the tool in or out of the opening 63 or 64 in its holder 61, or by changing the adjustment between the arms 67 and 71 or 67^a and 71^a by loosening the clamping screws 70.

After the pitch tools are correctly adjusted at both sides of the machine, the tools may be simultaneously moved outward by pulling down 20 on the rod 75, should this be desirable in starting up the machine or for any other reason, or they may be simultaneously and permanently adjusted inward or outward by changing the setting of the stop collar 77.

25 The rod 75 may be operated either manually or automatically, the latter being desirable in winding coils of varying pitch.

In Figs. 10 and 11 I have shown a modified and somewhat simpler construction for simultaneously adjusting the pitch tools. In this construction, the inner end of each pitch tool rod 60 is inserted in an opening 80 in the outer end of a tool slide 81 or 82, and is adjustably secured therein by a clamping screw 83. The slide 81 35 has a stud 83^a mounted therein, which extends freely outward through a slot 84 in the slide 82.

At its outer end, the stud 83^a has a pin-and-slot connection to the upper end of the upright arm of a bell crank 85, mounted on a fixed pivot 40 86. A similar stud 87 in the slide 82 has a pin-and-slot connection to a second bell crank 88 mounted on a second fixed pivot 89. An actuating rod 90 is pivoted on a stud 91 which extends through a slot in the horizontal arm of 45 the bell crank 85 and is fixed in the horizontal arm of the bell crank 88.

By vertical adjustment of the rod 90, the slides 80 and 82 and the pitch tool rods 60 may be simultaneously and equally adjusted in opposite 50 directions. One or more clamping screws 92 may be provided for holding the adjustment, if so desired.

The simpler construction in Figs. 10 and 11 thus presents similar advantages to those described with respect to the constructions shown in Figs. 6 to 9.

The details of construction of my improved machine having been made clear, it will be noted particularly that I have provided improved, reliable and efficient means for simultaneously driving independently separable and angularly adjustable feed rolls, and that I have also provided improved and effective devices for either separately or simultaneously displacing or adjusting the pitch tools at the two sides of a duplex coiling machine.

Having thus described my invention and the advantages thereof, I do not wish to be limited to the details herein disclosed, otherwise than as set forth in the claims, but what I claim is:

1. In a duplex wire coiling machine, a fixed frame, separate coiling apparatus at each side of said frame including two separate pitch tools positioned at opposite sides of the frame, means 70 to separately adjust said pitch tools toward and

away from the sides of said frame, and means to simultaneously adjust both of said pitch tools in opposite directions toward and away from the sides of said frame.

2. The combination in a wire coiling machine as set forth in claim 1, in which said latter means comprises separate pitch tool holders, bell cranks for said holders, and a single means to move both bell cranks and to thereby move both holders simultaneously in opposite directions.

3. The combination in a wire coiling machine as set forth in claim 1, in which said latter means comprises separate pitch tool holders, bell cranks for said holders having adjacently located arms, spring means to move said adjacent arms of said bell cranks in one direction, and a single means to move said bell crank arms in the opposite direction.

4. The combination in a wire coiling machine as set forth in claim 1, in which said latter means comprises separate pitch tool holders, bell cranks

for said holders having adjacently located arms, spring means to move said adjacent arms of said bell cranks in one direction, a single means to move said bell crank arms in the opposite direction, and an adjustable stop to limit the spring-actuated movement.

5. The combination in a wire coiling machine as set forth in claim 1 in which each pitch tool is adjustably secured in a separate tool slide, and 10 in which a single actuating device is effective to move both slides simultaneously and equally in opposite directions.

15 6. The combination in a wire coiling machine as set forth in claim 1 in which each pitch tool is adjustably secured in a separate tool slide, and in which a single actuating device is effective to move both slides simultaneously and equally in opposite directions, and in which clamping means is provided to retain said pitch tools and slides in 20 a selected relation.

CARL E. SPAULDING.
